Larry Lacy ATTORNEY.

UNITED STATES PATENT OFFICE.

EDWARD W. GROGAN, OF CLARENDON, TEXAS.

WRENCH.

1,372,618.

Specification of Letters Patent. Patented Mar. 22, 1921.

Application filed April 29, 1920. Serial No. 377,594.

To all whom it may concern:

Be it known that I, EDWARD W. GROGAN, a citizen of the United States, residing at Clarendon, in the county of Donley and State of Texas, have invented certain new and useful Improvements in Wrenches, of which the following is a specification.

This invention relates to improvements in wrenches of the sliding jaw type.

10 An important object of this invention is to provide a wrench having novel means whereby the same may be readily and conveniently secured in an adjusted position.

15 A further object of the invention is to provide a wrench of the sliding jaw and traveling fulcrum type having novel means whereby the grip of the jaws on the work is strengthened as the pressure applied to the handle is increased.

20 A further object of the invention is to provide a wrench of the class described which is of highly simplified construction, efficient in use and cheap to manufacture.

25 Other objects and advantages of the invention will be apparent during the course of the following description.

In the accompanying drawing forming a part of this application and in which like numerals are employed to designate like 30 parts throughout the same,

Figure 1 is a perspective of the improved wrench,

Fig. 2 is a central vertical longitudinal section through the same.

35 In the drawing wherein for the purpose of illustration is shown a preferred embodiment of the invention, the numeral 5 generally designates the stock of a wrench which as illustrated, is provided with a stationary 40 jaw 6 at its forward end. A second jaw 7 is provided with an opening 8 slidably receiving the shank or stock 5 of the wrench. As illustrated particularly in Fig. 2, one wall of the opening 8 is provided with a 45 transverse groove 10 which receives a transversely extending tooth 12 having its exposed portion pointed and engaging a plurality of transverse teeth 14 formed on the rear side of the shank 5. It will be noted that the transversely extending locking 50 tooth or strip 12 is triangular in cross section and is securely held within the groove 10 by engagement with the undercut side walls of said groove. The wall of the opening 8 opposite the transversely extending tooth 12 is inclined longitudinally, as indi-

cated at 15, to a point rearwardly of said tooth 12 so as to form a shoulder 16 which, as illustrated in Fig. 2, engages the adjacent longitudinal edge of the shank and is slid- 60 able with relation to the same.

A rearwardly extending longitudinally curved arm 18 is formed integral with the movable jaw 7 and is provided with a rectangular sleeve 20 which slidably receives 65 the shank 5 and is considerably greater in interior dimension than the width of the shank so that the sleeve may partake of a limited transverse movement with relation to the shank. The rear portion of the arm 70 18 is normally held in contact with the adjacent longitudinal edge of the shank 5 by a longitudinally curved leaf spring 22 secured to the opposite side of the sleeve 20 by a rivet 24 or other suitable fastening 75 means.

When it is desired to adjust the movable jaw along the shank 5, it is merely necessary to press the rear side of the sleeve 20 inwardly, as indicated in dotted lines in Fig. 80 2, so that the forward portion of the jaw is moved transversely of the shank whereby the locking tooth 12 is removed from engagement with the teeth 14. As the side of the sleeve having the longitudinally curved 85 leaf spring is moved inwardly, the shoulder 26 rearwardly of the tooth 12 is employed as a fulcrum. When the sleeve 20 is manually moved transversely of the shank, the rearwardly extending arm 18 does not interfere with its movement since the same has its central portion spaced from the shank.

The jaw 7 may be limited in its movement longitudinally of the shank by a stop element 25 which may be in the form of a 95 screw bolt. As the jaw 7 is moved rearwardly the stop element 25 is engaged by the rear side of the jaw 7 so that the removal of the jaw from the shank without first removing the stop element, is rendered 100 impossible.

With reference to the foregoing description it will be noted that the grip exerted by the jaws upon engaging a bolt or other piece of work is strengthened as the pressure applied to the handle of the shank is increased. This is accounted for by the fact that the transverse tooth 12 is more tightly drawn into engagement with the teeth 14. When the movable jaw is adjusted to the 110 desired place on the shank and the pressure removed from the spring 22, the jaw auto-

matically locks itself and is firmly held in place when brought into engagement with a nut. It will be noted also that a wrench constructed in accordance with this invention is capable of a variety of adjustments and may be conveniently and readily engaged with nuts and the like.

Having thus described the invention, what is claimed as new is:

- 10 A wrench comprising a shank having one edge smooth and provided along a portion of its opposite edge with transverse teeth, a stationary jaw at one end of the shank extending from the smooth edge thereof, a 15 movable jaw having an opening therethrough to receive the shank, the wall of the said opening presented to the teeth on the shank carrying a tooth near the working face of the jaw to interengage with the teeth

on the shank and the opposite wall of said opening being inclined toward the smooth edge of the shank from the working face of the jaw to the back thereof and defining a shoulder at the back of the jaw slidably engaging the shank and upon which the jaw 25 may rock, an arm extending from said shoulder and having a flat portion at its free end bearing upon the smooth edge of the shank, a sleeve extending from the free end of said arm around the shank and having a 30 length interiorly greater than the width of the shank, and a spring carried by said sleeve and bearing upon the shank whereby the flat portion of said arm is normally held against the smooth edge of the shank. 35

In testimony whereof I affix my signature.

EDWARD W. GROGAN. [L. S.]
